(57) **CLAIM**

The ornamental design for a semiconductor device, as shown and described.

DESCRIPTION

FIG. 1 is a front view of the semiconductor device, showing my new design;

FIG. 2 is a rear view thereof;

FIG. 3 is a right-side view thereof;

FIG. 4 is a left-side view thereof;

FIG. 5 is a top view thereof;

FIG. 6 is a bottom view thereof;

FIG. 7 is a front top right side perspective view thereof;

FIG. 8 is a rear bottom left side perspective view thereof;

FIG. 9 is a front top left side perspective view thereof; and,

FIG. 10 is a rear bottom right side perspective view thereof.

The broken lines in the drawings illustrate portions of the semiconductor device that form no part of the claimed design.
